UNITED STATES PATENT OFFICE.

HENRIQUE C. KENNEDY, OF PHILADELPHIA, PENNSYLVANIA.

BOTTLE-WASHING MACHINE.

SPECIFICATION forming part of Letters Patent No. 744,560, dated November 17, 1903.

Application filed December 8, 1902. Serial No. 134,230. (No model.)

To all whom it may concern:

Be it known that I, HENRIQUE C. KENNEDY, a citizen of the United States, residing in the city and county of Philadelphia, State of Pennsylvania, have invented a new and useful Improvement in Bottle-Washing Machines, of which the following is a specification.

My invention consists of an improved construction of a bottle-washing machine where-
10 in a rotary motor is employed to rotate the bottle-washing devices and provision is made for causing hot or cold water to be directed upon the washing device and into the interior of the bottle when the latter is pressed upon
15 said washing device.

The invention also consists of a novel construction of mechanism whereby water is directed upon the brush and the interior of the bottle when the latter is pressed upon said
20 brush.

It further consists of novel details of construction, all as will be hereinafter fully set forth and claimed.

Figure 1 represents a side elevation, partly
25 in section, of a bottle-washing machine embodying my invention. Fig. 2 represents, on an enlarged scale, a section on line *z z*, Fig. 1. Fig. 3 represents a front view of one of the buckets of the water-motor in detached
30 position. Fig. 4 represents a side view of Fig. 3. Fig. 5 represents a section on line *y y*, Fig. 3. Fig. 6 represents an end view of the device. Fig. 7 represents a view showing one end of the casing removed. Fig. 8 represents a perspective view of the bottle-washer.

Similar numerals of reference indicate corresponding parts in the figures.

Referring to the drawings, 1 designates an inlet-pipe for the motor, which latter enters
40 the lower portion of the casing 2 and is provided with a curved nozzle 3, which is adapted to discharge upon the buckets 4 of the water-wheel 5, which is contained within said casing 2 and is mounted upon the tubular shaft 6,
45 which revolves in suitable bearings in the casing 2.

7 designates a branch leading from the pipe 1 and containing the valve 8 therein, said branch leading into the pipe 9, which dis-
50 charges into the valve-casing 10, in which is located the valve 11, which is operated by the connection or lever 12, one end of which is se-

cured to said valve, while its lower end is connected to an end of the rod or arm 13, which is mounted in suitable bearings 14 and 15 and
55 is held in the desired position, so that the valve 11 is normally closed by means of the spring 16.

17 designates a plate which has the rods 18 and 19 projecting laterally therefrom and
60 adapted to enter the guides 20 and 21.

22 designates a tube which is adapted to rotate in unison with the tube 6 in suitable bearings or may be part of said tube 6 and having the stem 23 secured therein by the
65 set-screw or other fastening device 24, said stem carrying the bottle-washing brush 25.

Within the tube 22 is contained the spider or plate 26, which prevents the plate 17 and its adjuncts from being pushed inwardly,
70 said plate 26 contacting with the pivot 27, which is provided with a point or knife-edge, so that the revolution of the tube 22 is at all times easily accomplished, since the plate at first serves as a knife-point bearing for the
75 pivot. This pivot is provided with spirally-disposed grooves or passages to permit of the flow of the water through the tubular shaft 6.

In Figs. 3, 4, and 5 I have shown the preferred form of buckets employed, the same
80 consisting of the concave channels 28, which are provided with the arch-shaped recess 29 and the intermediate web 30, the general contour of said buckets being clearly understood from said Figs. 3 to 5, inclusive.

31 designates a pipe, suitably valve-controlled, which discharges into the valve-casing 10 and may be suitably connected with a suitable source of supply, such as hot water or cleansing material.

The operation is as follows: The water passes up through the pipe 1 to the nozzle 3, where it discharges against the buckets of the water-wheel 5 and causes the same to revolve. The bottle to be cleansed is placed on the brush
95 25 and force is applied to push in the same. The neck of the bottle contacting with the plate 17 forces the same inwardly in the direction indicated by the arrow and carrying with it the arm 13, which being connected
100 with the connection or lever 12 opens the valve 11. The valve 8 meanwhile in the pipe 7 is open in order that water from the pipe 1 will pass therethrough to the pipe 9 and

thence through the valve-casing 10 into the pipe 6 and is conducted to the interior of the bottle, it being noted that the water-wheel meanwhile is revolved and carries with it the 5 tubular shaft 6, which rotates and causes the brush 25 to rotate upon the interior of the said bottle. When the pressure from the bottle is removed, the plate 17 and its adjuncts are caused to move in the opposite direction, 10 so that the valve 11 is closed, and no water will pass through the tubular shaft 6 and pipe 22 until the next operation. If desired, by properly manipulating the valve in the pipe 31 hot water or other suitable cleansing material can be likewise inserted into the bottle, 15 it being noted that the arch-shaped recess 29 in the buckets permits the same to freely pass the nozzle 3, while the pipe 22 passes from the casing 2 for the discharge of 20 the next water. By reason of the pivot 27 bearing upon the plate 26 a practically frictionless bearing is provided which permits easy and free revolution of the water-wheel 5 and the shaft 6 and brush 25, the pipe 32 communicating with the interior of the casing 25 and serving as an exhaust for the water.

It will be apparent that various changes may be made by those skilled in this art which will come within the scope of my invention, and I do not, therefore, desire to be limited in every instance to the exact construction herein shown and described.

Having thus described my invention, what I claim as new, and desire to secure by Letters 35 Patent, is—

1. In a bottle-washing machine, a water-wheel, a tubular shaft connected therewith, friction-reducing bearing for said shaft having water-passages, a brush suitably carried 40 by said shaft, a valve disposed within and controlling the interior of said tubular shaft, a sliding frame adapted to be engaged directly by the bottle, and a direct connection between said frame and valve whereby pressure of the bottle against the frame actuates 45 said valve.

2. In a bottle-washing machine, a casing, a water-wheel mounted therein, a tubular shaft upon which said water-wheel is mounted, 50 a brush mounted upon said shaft, a friction-reducing bearing for said shaft having passages for the water, a valve disposed within and controlling the entrance to said shaft, a pipe for conducting water to actuate said 55 water-wheel, a branch pipe leading therefrom conducting water to said tubular shaft, and

a pipe connected with said branch pipe in alignment with the tubular shaft for admitting cleansing fluid thereinto.

3. In a bottle-washing machine, a casing, 60 a tubular shaft journaled in said casing, a friction-reducing bearing for said shaft having passages for the water, a water-wheel mounted on said shaft, a brush carried by said shaft, a valve controlling the admission 65 of fluid to said shaft, a plate movably connected with said casing, a guide-rod mounted in bearings in said casing, connections between one end of said guide-rod and the valve, and a spring around said guide-rod between 70 its bearings in the casing for normally holding said valve closed.

4. In a bottle-washing machine, a casing, 75 a tubular shaft journaled in said casing, a water-wheel mounted on said shaft, a brush carried by said shaft, a valve controlling the admission of fluid to said shaft, a plate movably connected with said casing, a guide-rod mounted in bearings in said casing, connections between one end of said guide-rod and 80 the valve, a spring around said guide-rod between its bearings in the casing for normally holding said valve closed, a pipe for conveying water to said water-wheel, a branch pipe leading therefrom for admitting water 85 to said tubular shaft, and a pipe connected with said branch pipe for admitting hot water or other cleansing material to said tubular shaft, said valve controlling the flow through said last-mentioned pipe and the 90 branch pipe.

5. In a bottle-washing machine, a casing, 95 a tubular shaft journaled therein, a water-wheel mounted on said shaft, a brush carried by said shaft, a movable plate through which the shaft of said brush passes, a valve in said tubular shaft, means movable with said plate for actuating the said valve, and a pointed pivot within the tubular shaft.

6. In a bottle-washing machine, a casing, 100 a tubular shaft journaled therein, a water-wheel mounted on said shaft, a brush carried by said shaft, a movable plate through which the shaft of said brush passes, a valve in said tubular shaft, means movable with said plate 105 for actuating said valve, a pointed pivot within the tubular shaft, and a spider within the tubular shaft for co-operation with said pivot.
